COMBINED XYLOPHONE AND CARRYING APPARATUS

Filed 1. v. 21, 1929

UNITED STATES PATENT OFFICE

THOMAS R. GERHART, OF LAWRENCE, KANSAS

COMBINED XYLOPHONE AND CARRYING APPARATUS

Application filed November 21, 1929. Serial No. 408,792.

This invention relates to combined xylophone and carrying apparatus and has for its primary object the provision of a musical instrument of the character mentioned having apparatus for supporting such instrument in the operative or playing position on the body of the player.

One of the objects of the present invention is the provision of novel supporting apparatus for musical instruments of the percussion type and especially those instruments which it is necessary to dispose in a substantially horizontal position while the same is being played.

15 An even further object of this invention is to provide a combined xylophone and carrying apparatus therefor which may be adjusted to suit the size of the player and may be moved toward or from the player in such 20 a manner that the position of the instrument is substantially the same as is normally maintained when the xylophone or the like is not being supported and carried along by the player.

25 A still further object of the instant invention is to provide apparatus for supporting a xylophone or similar musical instrument in the proper operative position which is adjustable, inexpensive to manufacture, extremely effective in its operation, comfortable to wear, and does not create discomfort to the player when the same is worn.

It is well known by musicians that it is desirable to have percussion instruments in bands but in view of their character it has heretofore been practically impossible to use the same because of a lack of equipment of the proper character.

35 In view of the above desirable requirement and the several objects enumerated, it is the basic intention of this invention to provide suitable apparatus of the character set forth and the same has been shown in one embodiment in the accompanying drawings, where- 40 in

Figure 1 is a perspective view of a combined xylophone and carrying apparatus made in accordance with this invention showing the same in the proper related position as though the same were being worn by a 50 player.

Fig. 2 is an enlarged detailed fragmentary view of the adjustable bracket which joins belt and frame the nature of the view being that of a fragmentary inverted plan. 55

Fig. 3 is a vertical cross section showing the adjustable nature of the bracket and but a portion of the body encircling belt, and

Fig. 4 is an enlarged detailed view of the 60 slidably inter-connected frame and bracket the same being a view taken as a cross section on line IV—IV of Fig. 3.

Like reference characters refer to similar parts throughout the several views of the drawings wherein is illustrated the preferred 65 embodiment of the invention.

The numeral 6 designates the well known 70 frame of a xylophone or the like which is equipped with the well known series of tone blocks 8 carried by the frame 6 in the well known manner. As shown in Fig. 1 frame 6 has a series of tone block supporting frame elements which in turn are supported by transverse elements 10 which should project slightly beyond the main longitudinal frame 75 elements as shown in Fig. 1.

The relative position of xylophone and player is very well established in the art and it is to maintain this relative position that the novel supporting apparatus is designed. 80 Since different players desire that the distance from the body be varied, a novel, adjustable bracket has been provided to join a body encircling belt 12 which carries a plate 14 at the front of the wearer when the belt is 85 in position. Any suitable means for securing plate 14 to belt 12 may be employed. In this instance belt 12 is merely threaded through openings formed in plate 14 as at 16. Plate 14 should have a bracket engaging 90

member 18 to receive the down-turned end 20 of bracket 22 when the frame 6 of the xylophone is being supported for playing. The end 20 of bracket 22 slidably engages member 18 in a manner which allows quick removal when it is desired to lower the xylophone to an inoperative position.

To properly fulfill one of the objects of this invention by way of making the frame 6 assume the desired position away from the body of the wearer, bracket 22 has been connected to frame 6 by adjusting mechanism which may be of the form shown in detail in Figs. 2, 3 and 4. This mechanism should have a flanged channel 24 rigidly secured as at 26 to the lower side of frame 6. The re-bent edges of channel 24 slidably supports bracket 22 and allows free longitudinal movement when plunger 28 is moved out of engagement with holes 30 formed in channel 24. To yieldably maintain plunger 28 in the locked position, a spring 32 should be provided secured at one end as at 34 to bracket 22.

As clearly shown in Figs. 3 and 4 plunger 28 normally rests in opening 36 through bracket 22 and when said opening 36 registers with any one of holes 30 plunger 28 is moved by spring 32 to engage the particular hole 30 with which opening 36 has registered. Thus the adjusting mechanism supporting bracket 22 permits movement of frame 6 predetermined and varying distances from the belt 12. This adjustment can be made without removing the belt and without removing the later described shoulder strap.

To establish an effective three point suspension for the xylophone, an up-standing arm 38 should be provided at the side of frame 6 opposite from bracket 22. These arms 38 should be adjacent the corners of frame 6 and in the instance shown are pivotally connected as at 40 to transverse elements 10. This pivotal connection allows the movement of arms 38 to a folded position parallel with elements 10 when it is desired to pack the instrument. The operative position of arm 38 is shown in Figs. 1 and 3 and is substantially perpendicular to frame 6.

A pair of shoulder straps 42 should be provided to connect the plate 14 carried by belt 12 and arms 38. To compensate for varying sizes of players, length adjusting devices such as buckles or the like 44 are provided to allow the operator to lengthen or shorten shoulder straps 42 so that the side of the frame 6 opposite from bracket 22 may be raised or lowered to level the instrument ready for playing.

One end of straps 42 is coupled to the upper ends of up-standing arms 38 carried across the shoulders of the player, crossed in the back and coupled to plate 14 on either side of bracket 22. These couplings may be through the use of ordinary snap hooks as shown at 46 which permits of

quick assembling and dis-assembling the entire apparatus. It is obvious that the downward pressure exerted upon belt 12 by bracket 22 through plate 14 is somewhat relieved and equalized through the upward pull of shoulder straps 42 at points adjacent bracket 22. Manifestly the three point suspension and the equalized distribution of the weight of the instrument affords in this device an exceptionally efficient and comfortable apparatus by means of which a xylophone or similar instrument might be carried and played in a band in a manner not unlike any other well known band instrument.

Many modifications in the specific structure of a device embodying this invention might be made without departing from the spirit thereof or the scope of the appended claims.

What is claimed and desired to be secured by Letters Patent is:

1. In a device of the character described, a xylophone frame, a body encircling belt, a plate carried by said belt, a bracket projecting from one side of said frame to join said plate, adjusting mechanism for the bracket for selectively maintaining said frame and plate in varying spaced relation, a pair of shoulder straps connecting the plate and xylophone frame and length adjusting devices for said shoulder straps, said straps being coupled to said xylophone frame at the side opposite from said projecting bracket, said releasable means for the bracket including a flanged channel secured to said frame and slidably supporting said bracket, a series of holes formed in said channel and a plunger carried by the bracket to selectively engage the said holes.

2. In a device of the character described, a frame, a body encircling belt, a bracket slidably supported by said frame and projecting from one side thereof to join said belt, releasable means for securing said bracket in any one of a series of positions after the same has been moved to space said frame and belt apart, a pair of up-standing arms carried by said frame at the side opposite from said bracket and a pair of shoulder straps joining said body encircling belt and said up-standing arms respectively, said releasable means for the bracket including a flanged channel secured to said frame, said bracket being supported thereby for longitudinal reciprocating rectilinear movement, a series of holes formed in said channel, a plunger to selectively engage each hole respectively and a spring supporting said plunger to yieldably maintain the same in engagement with one of said holes.

3. In a device of the character described, a xylophone frame, a body encircling belt, a plate carried by said belt, a bracket projecting from one side of said xylophone frame

to removably engage said plate, a pair of up-standing arms pivotally supported by said xylophone frame at the side thereof opposite from said bracket and adjacent the two corners respectively of said frame, a pair of shoulder straps connecting the plate and said up-standing arms pivotally supported, said arms being movable from the position perpendicular to said frame to a position parallel with one side thereof.

10 In testimony whereof, I hereunto affix my signature.

THOMAS R. GERHART.
